CLAIM

The ornamental design for a clip for a writing instrument or the like, substantially as shown and described.

DESCRIPTION

FIG. 1 is a front elevational view of a clip for a writing instrument or the like showing my new design;
FIG. 2 is a right side elevational view, the left side being a mirror image thereof;

FIG. 3 is a rear elevational view thereof;

FIG. 4 is a top plan view thereof;

FIG. 5 is a bottom plan view thereof; and

FIG. 6 is a perspective view thereof.
